CLAIM

The ornamental design for a cover for an exit alarm lock, as shown and described.

DESCRIPTION

FIG. 1 is a perspective view of an exit alarm lock showing our new design;

FIG. 2 is a front view of a design of exit alarm lock according to the present invention.

FIG. 3 is a top view of a design of exit alarm lock according to the present invention;

FIG. 4 is a bottom view of a design of exit alarm lock according to the present invention;

FIG. 5 is a right side view of a design of exit alarm lock according to the present invention; and,

FIG. 6 is a left side view of a design of exit alarm lock according to the present invention.

The broken line disclosure is for illustrative purposes only and forms no part of the claimed design. The surface(s) or portion(s) of the article not shown in the drawing or described in the specification form(s) no part of the claimed design.
